UNITED STATES PATENT OFFICE.

CHARLES RYDER, OF COVINGTON, KENTUCKY, ASSIGNOR TO THE CORCORAN-VICTOR COMPANY, OF CINCINNATI, OHIO, A CORPORATION OF OHIO.

LAMP.

1,266,164.

Specification of Letters Patent.

Patented May 14, 1918.

Application filed July 30, 1917. Serial No. 183,390.

To all whom it may concern:

Be it known that I, CHARLES RYDER, a citizen of the United States, and a resident of the city of Covington, in the county of 5 Kenton and State of Kentucky, have invented certain new and useful Improvements in Lamps, of which the following is a full, clear, and exact description, reference being had to the accompanying drawings, forming 10 part of this specification.

My invention relates to oil lamps, of the type wherein the font is detachable from the lamp body and is locked in place against jarring out. Such lamps are usually employed as "tail lights" and "side lights" in 15 carriages and automobiles, as in these uses the necessity of the removable font, capable of being securely locked in place, is important.

20 It is the object of my invention to provide an oil font attachment for such lamps, which is "fool-proof" to a high degree such that when installed, the failure of the operator to securely lock the attachment will 25 not result in the dropping off of the font.

This object and other advantages to be 30 noted I accomplish by that certain construction and arrangement of parts to be herein-after more specifically pointed out and claimed.

In the drawing,

Figure 1 is a side elevation of the lamp complete.

Fig. 2 is a detail side elevation of the 35 lower end of the lamp body partly broken away to show the mounting channel for the locking ring and the inclined bearing edges for the pins on the font.

Fig. 3 is a horizontal section taken through 40 the lamp body just above the locking ring, showing the same in unlocked position with the font removed.

Fig. 4 is a sectional view of the lamp taken horizontally through the said locking 45 ring, with the same in locking position, with the font in place.

Fig. 5 is a detail top plan view of the locking ring partly broken away.

Fig. 6 is a perspective view of the part shown in Fig. 5.

Fig. 7 is a perspective view of the lamp font.

The lamp body 1 is provided with the depending cylindrical portion or socket 2, into which the font is to be thrust and in 55 which the locking of the font in place is to be accomplished. The lamp font has an oil pot portion 3, a cylindrical portion 4 which fits into the depending cylindrical portion or socket of the lamp body, the wick tube or 60 burner 5 and the wick shaft 6.

On the cylindrical portion 4 of the font are a plurality of pins 7 (three by preference), and the wick shaft is alined with one of the pins when the font is to be inserted 65 into the lamp body.

The edges of the body at the lower end of the socket portion 2 are turned up inwardly so as to form a channel 8. The edges are cut at 9, 9, to form clearances for the pins 7. 70 The metal so inturned is cut away to form sloping walls 10, 10, so that when the font is inserted with the pins entering in the cuts at 9, 9, the turning of the font will bring the pins up along the sloping walls, and thus elevate the font in the socket so that it abuts 75 firmly against the base of the same.

Set in the inside of the socket portion of the lamp body is a semicircular plate 11, which seats and slides in the channel 8. 80 This plate has a vertical cut 12 which receives one of the pins on the font and also the wick shaft when the font is inserted. It has also a screw 13 set into it, on which screw is mounted the clamp nut 14. 85

The socket is cut with a vertical slot 15 to permit the passage of the wick shaft, and a transverse slot 16 communicating therewith, to give a clearance for the wick shaft so as to permit of the font being turned within 90 the socket. It can thus be seen that when the wick shaft is thrust up into the slot in the socket and also the registering slot or cut 12 in the plate 11, the font can then be turned part way around thereby moving the plate 11, 95 sliding the wick shaft to the end of the

branch slot 16, and drawing the font tightly up against the socket base, by means of the pins, as heretofore described.

The socket is provided with a horizontal slot 17 for the passage of the screw 13 on the sliding plate, and to tighten the sliding plate in desired position the clamping nut 14 is turned down on the screw against the outside socket wall.

10 As so far described, the security of the device is dependent upon the care of the operator in inserting and locking the font in place. If he should not turn it sufficiently, or should leave the nut 14 loose, the 15 font will drop out and become lost if the use is on an automobile, particularly when used as a "tail light" which is not within the range of the driver's vision.

16 A spring device is therefore provided 20 with which to insure the proper mounting of the font, and hold the font against falling out whether the clamping screw is turned up or not.

17 The semicircular sliding plate is cut with 25 a slot 18 and secured against the back or inside surface of the plate is a spring 19. The screw 13 may be used for securing this spring in place, thereby avoiding a multiplicity of parts and operations. The spring 30 has a nose 20 bent in it which extends through the slot 18. The cylindrical socket portion of the lamp body is cut with two slots 21 and 22, to allow the spring nose to protrude.

35 When the sliding plate is in locking position with regard to the font, the spring nose will extend out of the slot 21. When the said plate is in releasing position, the nose will be in the slot 22. This latter position 40 of the spring nose is to permit the font to be withdrawn from the socket, since if the spring nose were not given this clearance, the close fitting portion of the font would not be removable from the socket.

45 When the operator inserts the font, he turns the font in his hand to lock it. Owing to the configuration of the nose on the spring, it will snap out of the slot 22. The font will then move the sliding plate until 50 the nose snaps into the slot 21. This will stop the movement of the font and will indicate that the font is locked in place.

55 The operator should then tighten up on the clamp nut. If he should fail to do this, however, the plate would be held by the spring. The nut need not be used with the rest of the combination unless so desired, but it adds security, and also prevents the device from rattling.

60 The spring takes entire care of the sliding plate and thus locks the font in position. The snapping of the spring into the two slots in the socket portion of the body indicates

both open and shut position to the operator, which is considerable of a convenience.

65

The device is simple and free from the considerable difficulties of adjusting and assembling which are to be found in the lamps of the prior art with which I am familiar.

Having thus described my invention, what 70 I claim as new and desire to secure by Letters Patent, is:—

1. In a lamp, a lamp body, a font, adapted to fit into the lamp body, a sliding plate in the lamp body, means on the lamp body and the font for securing them together by a twisting movement, means on the font to engage the sliding plate with means to lock the plate to the lamp body, and releasable spring means on the plate to snap into place 80 at the desired position to indicate the locking position of the plate and to hold the font in position secured to the lamp body.

2. In a lamp, a lamp body, a font adapted to fit into the lamp body, a sliding plate in the lamp body, means on the lamp body and the font for securing them together by a twisting movement, means on the font to engage the sliding plate, with means to lock the plate to the lamp body, and releasable 90 spring means to hold the plate at position for insertion of the font into the body, and at position when the font has been twisted to bring the securing means into operation and to indicate the locking position of the 95 plate.

3. In a lamp, a lamp body having an in-turned lower edge, a font having mounting pins thereon, slanting notches in the in-turned flange to engage the pins, whereby 100 the body and font may be secured together by a twisting movement of the font, a plate supported in the inturned flange, means on the plate and the font to come into engagement, with means to lock the plate to the 105 lamp body, and a releasable spring catch for the sliding plate to retain it in position with the font in engagement therewith and twisted to secured position and to indicate the locking position of the plate.

110

4. In a lamp, a lamp body having an in-turned lower edge, a font having mounting pins thereon, slanting notches in the in-turned flange to engage the pins, whereby the body and font may be secured together 115 by a twisting movement of the font, a plate supported in the inturned flange, means on the plate and the font to come into engagement, and a spring on the plate having a nose, slots in the body to releasably receive 120 said nose, said slots positioned to retain the sliding plate when the font is in secured position and in position for removal.

5. In a lamp, a lamp body having an in-turned lower edge, a font having mounting 125 pins thereon, slanting notches in the in-

turned flange to engage the pins, whereby the body and font may be secured together by a twisting movement of the font, a plate supported in the inturned flange, means on the plate and the font to come into engagement, and a spring on the plate having a nose, slots in the body to releasably receive said nose, said slots positioned to retain the

sliding plate when the font is in secured position and in position for removal, said 10 plate having a screw extending through the body and slidable in a slot thereof, and a clamping nut on said screw to manually clamp the plate in desired positions.

CHARLES RYDER.
